METHOD OF COATING SHEET METAL CANS

James H. O'Neil, Syracuse, N. Y., assignor to
Continental Can Company, Inc., New York,
N. Y., a corporation of New York

Application August 17, 1936, Serial No. 96,502

3 Claims. (Cl. 91—68)

The invention relates to new and useful improvements in a method for coating sheet metal cans.

An object of the invention is to provide a method of coating sheet metal cans on the interior thereof with a thermo-plastic material whereby a coating of substantially uniform thickness completely covering the interior of the can may be provided.

10 A further object of the invention is to provide a method of coating a can having a neck portion terminating in a sealing lip wherein a vacuum creating means may be utilized for drawing air from the can in such a way as to remove excess 15 coating material accumulating on the inner and outer faces of the sealing lip during the draining thereof.

In the drawings—

Figure 1 is a vertical sectional view showing a 20 can in inverted position for draining the excess coating from the can;

Fig. 2 is a vertical sectional view of a can having a coating applied to the inner surface thereof by the method embodying the invention;

25 Fig. 3 is a view in vertical section showing a portion of an apparatus for carrying out the improved method;

Fig. 4 is a view showing a can after draining and prior to the subjecting of the same to the 30 suction means for drawing the air from the can, and

Fig. 5 is a view similar to Fig. 4, but showing the air drawn from the can and the excess wax 35 accumulating at the inner and outer surfaces of the sealing lip removed by the flow of air from the can.

In the patent granted Alfred L. Kronquest, June 15, 1937, No. 2,084,093, there is shown a machine for coating cans with a thermo-plastic 40 sealing material. The can coated is of the type wherein the top end is provided with a raised cone-shaped portion terminating in a neck having a sealing lip and a shoulder so that a crown cap can be used for closing the can. The can is coated with a thermo-plastic material, preferably of petroleum wax, which has a melting point of 160° F. or above. The wax is reduced to a fluid form by heating and is then discharged through a nozzle into the can while it is inverted, and thus the entire inner surface of the can is flooded with the fluid wax. As the excess wax drains from the can, it will form a uniform layer over the greater portion of the inner surface of the can, due to the wax adhering to the metal. When the can has a dome-shaped bottom, the draining of the wax will cause a drop of wax to form at the center of the inverted dome. If the can is inverted quickly while the wax is in fluid form, this drop of wax will flow so as to form a sub-

stantially uniform layer on the inner surface of the dome. During the draining, wax will accumulate at the inner surface of the sealing lip forming a thickened coating which is likely to be thrown from the can on to the outer face of the lip when the can is quickly inverted.

The present invention has to do particularly with the removing of this excess wax accumulating on the inner and outer surfaces of the sealing lip of the can. It is believed that the invention will be better understood by a detail description of the can and the apparatus for carrying out the improved method of coating the interior of the can.

In Fig. 1 of the drawings, a can is shown in vertical section which has been coated and is in draining position. The can consists of a body portion 1 which is, as shown, cylindrical in cross section. The bottom end 2 is secured to the body by a double seam 3. This bottom end is dome-shaped as indicated at 4. At the top end of the can body is a closure end 5 which is double-seamed to the can body at 6. This top end has a cone-shaped portion extending above the double seam and terminating in a neck 7. The neck is inturned to form a sealing lip 8 and a locking shoulder 9, so that a crown cap may be applied to the sealing lip and the flange thereof crimped underneath the shoulder 9 for sealing the can. In carrying out the invention, the thermo-plastic material is reduced to fluid form by heating and is then flooded over the inner surface of the can through a nozzle which is projected into the can as shown in the Kronquest patent above referred to. As the surplus material drains from the can, a thin film or lining of the thermo-plastic material will adhere to the inner surface of the can. The lining is indicated at 10 on Fig. 1 of the drawings. During this draining of the petroleum wax from the can, a drop of wax will form as indicated at 11. The sealing lip 8 of the can extends inwardly substantially horizontally, and the inner edge is preferably rolled back upon the inner surface of the sealing lip. This forms more or less of a trap so that the wax draining from the can will accumulate as indicated at 12 in Fig. 4, and thus form an excess of wax which is objectionable. Some excess wax may adhere to the outer surface of the lip 8 during draining which is also objectionable. It is found that if the can while the wax is still in a semi-fluid condition, is turned back to an upright position, the drop of wax accumulating at the center of the dome will distribute itself evenly over the dome-shaped bottom. When, however, the can is turned from an inverted position to an upright position quickly, this accumulation of wax at the inner surface of the sealing lip which is indicated at 12 in the drawings, is likely to be thrown from the can mouth and lodge on the 60

outer side of the lip. It is very objectionable to have wax on the outer face of the sealing lip, for the reason that when the crown cap is forced into contact with the sealing lip, it will prevent 5 an efficient seal.

The purpose of the present invention is to provide a method whereby this excess wax on the inner surface of the sealing lip may be removed so as to leave a thin lining in the region of the 10 sealing lip which will not be thrown from the can when it is turned to a righted position. The apparatus as shown in the drawings includes a standard 13 around which a turret 14 is mounted for rotation. This turret has an outwardly projecting portion 15 on which is mounted a series 15 of nozzles 16. These nozzles are all of similar construction and a description of one will answer for the others. The nozzle is mounted on a sleeve shank 17 which fits within a recess formed in the member 15. A set screw 18 clamps the nozzle firmly in the recess. This member 15 is provided with a port 19 and the sleeve shank of the nozzle has an opening 20 therein connected to the port 19. The nozzle 16 is tapered and the can indicated at C in the drawings, is inverted over this 25 nozzle and rests on the nozzle. The can is fed into a pocket 21 in the turret and is held in the pocket by a guide rail 22. The shoulder 23 is so dimensioned relative to the nozzle that the can 30 body normally rests on the nozzle with the tapered portion thereof extending into the mouth of the can. The inner edge of the sealing lip contacts with the nozzle and this contact is maintained by the weight of the can body.

35 The nozzle has an annular recess 24 extending around the upper end thereof. A cap 25 extending into the nozzle overhangs this recess so as to form an annular channel. The nozzle 16 has a series of ports 26 which open into the sleeve 17 40 at their lower ends and into the channel 24 at their upper ends. It will be noted that when a can rests on the nozzle, the inner surface of the sealing lip at the inner edge thereof contacts with the nozzle just below the channel 24. The 45 port 19 is adapted to be connected to a suction creating means, and this will cause the air in the can to flow out through the ports 26. As the air flows out through the ports 26, it will follow the direction of the arrows indicated in Fig. 4, that 50 is, the air current will sweep down against the thickened layer of wax on the inner surface of the sealing lip, and the wax will be gradually taken up with the flowing air current until the 55 layer of wax is thinned as indicated in Fig. 5 of the drawings. The suction force can be adjusted so that the excess wax is removed and a thin layer of wax remains covering the inner surface of the sealing lip and the parts adjacent thereto when all of the air has been drawn from 60 the can. A continuation of the suction pull will cause air to press against the under face of the sealing lip as indicated by the arrows in Fig. 5, and this will raise the lip sufficiently from the 65 nozzle to permit air to pass into the mouth and out through the ports. This shifting of the air current to the outside of the sealing lip will remove any feather edge of sealing material extending around on to the outer face of the sealing lip so that there is only a thin even layer of wax 70 adhering to the inner edge of the sealing lip and the outer face thereof.

Inasmuch as the excess wax accumulating on the inner surface of the sealing lip has been removed, the can can now be quickly righted to 75 the position shown in Fig. 2, and the drop of wax

which accumulated on the center of the dome during draining, will as above noted, distribute itself evenly over the dome-shaped bottom.

Associated with the turret is a ring member 27 which is stationary and which has a chamber 5 28 therein. A port 29 at a certain section of this ring member 27 registers with a port 30 connecting with the port 19. This ring member 27 is connected to a pipe 31 which in turn is connected to a suitable vacuum creating means. The 10 wax taken up by the air current passes into the vacuum creating means and may be separated therefrom by a suitable strainer. There are a plurality of nozzles, and these nozzles, one after another, receive cans and are brought into operative connection with the vacuum creating means for carrying out the method above described. 15

The novel method consists in the closing of the can while in inverted position and the drawing of the air from the can by the suction means which 20 causes the air current to flow over the excess wax on the inner surface of the sealing lip so as to remove the same. The method also includes the step of drawing air across the outer face of the sealing lip after the air has been exhausted 25 from the can.

Having thus described the invention, what I claim as new and desire to secure by Letters Patent is:—

1. The method of coating a sheet metal can 30 having a neck portion terminating in a sealing lip with a thermo-plastic material, consisting in flowing the material while in fluid condition over the entire inner surface of the can, draining the surplus material from the can, subjecting the 35 can to a vacuum creating means for drawing air from the can, and directing the flow of the air from the can so that it passes across the material accumulating on the inner surface of the sealing lip during draining for reducing the coat- 40 ing thereon to a thin adhering covering.

2. The method of coating a sheet metal can having a neck portion terminating in a sealing lip with a thermo-plastic material, consisting in flowing the material while in fluid condition 45 over the entire inner surface of the can, draining the surplus material from the can, subjecting the can to a vacuum creating means for drawing air from the can, and directing the flow of the air from the can so that it passes across the material 50 accumulating on the inner surface of the sealing lip during draining for reducing the coating thereon to a thin adhering covering, and then causing air to flow across the outer face of said sealing lip for removing coating material there- 55 from.

3. The method of coating a sheet metal can having an inwardly curved dome-shaped bottom end and an outwardly extending cone-shaped top end, terminating in a neck portion provided with 60 a sealing lip, consisting in flowing the material in fluid condition over the entire inner surface of the can while held in an inverted position, permitting the material to drain from the can, subjecting the can to a vacuum creating means 65 for drawing air from the can and directing the flow of the air so that it passes across the material accumulating on the inner surface of the sealing lip during draining for reducing the coat- 70 ing thereon to a thin adhering covering, and subsequently placing the can in an upright position while the coating material is sufficiently fluid to permit excess material gathering at the center of the dome to be distributed over the dome.
